UNITED STATES PATENT OFFICE

GUY CARPENTER, OF NEW YORK, N. Y.

SPARK ARRESTER

Application filed April 22, 1924. Serial No. 708,149.

My invention relates to the art of producing devices adapted to arrest, cool and collect, the solid substances accompanying the gases in the products of combustion— particularly as applied to locomotive engines and, to a large extent, follows the principle and some of the structural elements disclosed and illustrated in my prior applications for patent numbers 693,185 and 693,186, filed February 16, 1924. However, this invention differs from the aforesaid inventions in that the spiral I employ is located in a different position (with relation to the fire box and smoke stack) and the smoke chamber 15 itself is subdivided in a different manner, and the stack is near the forward end thereof, and in addition to these changes I provide means to direct all the products of combustion into a spiral passage immediately as 20 they leave the fire box.

My invention may be more easily understood by reference to the accompanying drawing, which illustrates a preferred form of construction, and in which,—

25 Fig. 1 shows a longitudinal sectional view of the forward part of a locomotive engine fitted with my device, and

Fig. 2 shows a transverse sectional view taken on the line 2—2, in Fig. 1.

30 Reference now being had to the drawings forming a part of this application the numeral 10 indicates the fire tubes of a locomotive engine, the numeral 11 the smoke chamber, 12 the smoke stack and 13 the exhaust jet, all of which (except for the arrangement as herein illustrated) are more or less customary in the ordinary type of locomotive engine now in common use.

In the smoke chamber I have placed a 40 transverse partition 14, located slightly to the rear of the smoke stack 12, which partition has a large circular opening in its central portion, and a cylinder 15 fits within this opening and extends rearwardly from the 45 partition 14 to a point near the fire tubes 10. A cone-shaped member 16 extends from the inner end of the cylinder 15 rearwardly and outwardly to engagement with the inner wall of the smoke chamber 11. Within the cylinder 15 I have secured a second longitudinal

cylinder, or supporting member, 17, the two cylinders being of substantially the same length and disposed with relation to each other as shown. A helically formed member 18 is secured to this inner supporting member 17, its blade contacting and fitting flush against the inner surface of the outer cylinder 15. If a cylinder is used for this supporting member 17, one or both of its ends are closed, the only function of the said supporting member being to support the helically formed member 18. On the inner surface of the outer cylinder 15 I have secured a number of baffles 19 which, preferably, are so mounted as to oppose the flow of the gases, and adjacent each of these baffles I have provided an opening 20 through the wall of the said cylinder 15.

By the construction shown and described it is obvious I have created a chamber between the inner surface of the smoke box 11 and the outer cylinder 15, which chamber is closed at its forward end by the partition 14 and at its rear end by the cone-shaped member 16, and this chamber I designate as 70 my collecting chamber and indicate it by the numeral 21. The openings 20 through the wall of the cylinder 15, open into this chamber 21, and I have provided a door 22, at its base.

75 The jet 13 is, obviously, positioned centrally beneath the open end of the smoke stack 12, and in close proximity thereto.

In practical operation the jet 13 draws the products of combustion from the fire box 80 at a very high velocity. They pass through the cone-shaped member 16 into the cylinder 15, where they are forced around the helically formed member 18. This action produces a strong centrifugal force upon the 85 particles of solids, such as sparks, cinders and the like, in the products of combustion and they are, as a result, thrown outwardly against the inner surface of the cylinder 15, caught by the baffles 19 and pass through 90 the openings 20 into the collecting chamber 21, and may be removed therefrom by opening the door 22. The gases proceed on their way through the spiral passage formed by 95 the helically formed member 18 and the cyl- 100

nder 15 and into the stack chamber, and are expelled through the stack 12.

Having thus described my invention what I claim and desire to secure by Letters Patent of the United States, is:

In a spark arrester for locomotive engines employing a fire chamber; a smoke chamber; a transverse partition, provided with a central opening, mounted in the smoke chamber; a smoke stack; a cylinder fitted in the opening of the partition and extending rearwardly therefrom, there being openings in the wall of said cylinder; a helically formed member fitted in said cylinder; baffles secured to the inner wall of said cylinder, a baffle being adjacent each of the openings in the wall of the cylinder and an exhaust jet in the smoke chamber positioned below the smoke stack.
